UNITED STATES PATENT OFFICE

EDWIN HUMPHREYVILLE, OF LANCASTER, PENNSYLVANIA

HEAT CONSERVER

Application filed October 27, 1930. Serial No. 491,467.

This invention relates to heat conservers, showing in detail, the manner of adjusting to different size burners and securing thereto. and has for an object to provide a device for co-acting with the gas burner, of an ordinary gas range, or cooking stove, which shall 5 in an improved manner, direct the flame from the gas burner to the utensil located above the burner.

In the use of gas burners, as ordinarily employed, a considerable portion of the heat 10 is dissipated by the reason of the flame from the burner belling out, and escaping around and about the edges of the utensil. Attempts have been made to overcome this deficiency, but in general, such attempts have resulted 15 in the formation of dead air pockets immediately under the utensil which are insulating in nature, and in fact, waste the heat rather than conserve it.

The present invention, therefore, is directed to a sleeve which surrounds the burner, having air vents therein for the admission of secondary air, and formed to conduct the heat from the burner up to within a relatively short distance from the bottom 25 of the utensil, thereby conserving a much greater portion of such heat than ordinarily results from gas combustion.

An object of the invention is, therefore, to provide a band which shall be adjustable, 30 and which shall accommodate itself to burners of different sizes, to surround and embrace the burner, and to extend upwardly to the grid to direct products of combustion and air heated thereby, in a more direct path to 35 engagement with the bottom of the utensil.

The invention is directed to other objects and possesses other features of novelty and advantage, some of which, together with the foregoing, will be hereinafter more fully 40 set forth.

In the drawing:

Figure 1 is a top plan view of a conventional gas burner, and accessories, with the heat conserver applied thereto,

45 Figure 2 is a fragmentary sectional view, taken on line 2-2 of Figure 1,

Figure 3 is a detail view of the band, or sleeve, seen from the exterior, or convex side, and

50 Figure 4 is a top plan view of the band

Like characters of reference indicate corresponding parts throughout the several views. The heat conserver, which forms the subject matter of this application, is adapted to be associated with gas burner installations of various types, here represented by the burner proper A, the grid B, and stove top C. It is to be understood, however, that these features form no part of the present invention, but only the structure to which the invention is applied, and will vary with the particular construction of different makers, and the drawing is only illustrative of such devices.

The invention comprises a band 10, of flexible sheet metal, or the like, having slits 11, 70 formed therein, at spaced intervals throughout the major part of its length, and the sections of metal of alternate, or occasional strips, between the slits, stamped inwardly as indicated to form louvres 12. 75

In the drawing, these inwardly stamped strips have been shown as alternating with the sections remaining in plane with the band, but it is to be understood, that such proportion as may be chosen, may be so stamped inwardly.

At one end, the band is provided with a neck 13, reduced in width, to correspond substantially with the length of the slits 11.

The band 10, constructed as stated, which 85 forms the heat conserver of this invention, is applied to the burner by simply curving it about the exterior ends of the burner sections, as shown at Figure 1, and the louvres 12, 90 will be arranged to bear upon the tops of the arms of the burner, as shown to support the band in position. The band, having been curved about the burner, the reduced end 13 will be inserted through any one of the slits 11, which presents itself, and after being 95 drawn tight enough to provide the adequate support, the inwardly extending end is bent backwardly upon itself, as shown at 14, thus forming a lock to retain the device in position.

It will be obvious, that while the interval between the burners and the grid arms does not vary greatly in different types of burners, there will, nevertheless, be some variation, and it will be perfectly obvious that the louvres 12 may be bent sufficiently at the time of application to properly position the band, to engage snugly against the under side of the grid, as shown at Figure 2.

The products of combustion from the orifices of the burner, and the air heated thereby, will be directed upwardly by this encircling band, so that it will be delivered at a point more nearly in contact with the superimposed utensil than would otherwise be the case, and at the same time, permit the burner to be located at such distance below the utensil as to furnish complete combustion, before the products of combustion, and the heated air impinge upon the utensil. By the employment of this band, complete or relatively complete combustion is attained, and at the same time, products of combustion are directed to the point of use without dissipation. The louvres, about the circumference of this band, will serve by the introduction of air to prevent the flame from the burner engaging against the band, and will also tend to direct the flame and products of combustion inwardly toward the center, and therefore, toward the point of use.

Of course, the heat conserver, herein illustrated, may be modified in various ways without departing from the invention herein set forth and hereinafter claimed.

The invention is hereby claimed as follows:

1. The combination with a burner of a band having transverse slits forming louvres therein, and means at its opposite ends for interconnection to form a hoop, said louvres being compressible for seating upon the burner to hold the hoop at a height determined thereby.

2. The combination with a gas burner embodying a central inlet flue and flues branching therefrom and spaced apart, of a band adjustable to circumference to encircle the extremities of the arms, and louvres formed in the band and adapted to bear upon the extremities of the arms and maintain the band in encircling position.

3. The combination with a gas burner embodying a central inlet flue and flues branching therefrom and spaced apart, of a band adjustable to circumference to encircle the extremities of the arms, and inwardly struck louvres formed in the band and adapted to bear upon the extremities of the arms and maintain the band in encircling position.

4. The combination with a gas burner embodying a central inlet flue and flues branching therefrom and spaced apart, of a band adjustable to circumference to encircle the extremities of the arms, and louvres formed

in the band and compressible to vary the heights of certain of said louvres adapted to bear upon the extremities of the arms and maintain the band in encircling position.

5. The combination with a gas burner embodying a central inlet flue and flues branching therefrom and spaced apart, of a band adjustable to circumference to encircle the extremities of the arms, and inwardly struck louvres formed in the band and compressible to vary the heights of certain of said louvres adapted to bear upon the extremities of the arms and maintain the band in encircling position.

6. The combination with a gas burner embodying a central inlet flue and flues branching therefrom and spaced apart, of a band adjustable to circumference to encircle the extremities of the arms, and louvres formed in the band and compressible to vary the heights of certain of said louvres adapted to bear upon the extremities of the arms and maintain the band in encircling position at a height above the burner determined by the proportion of said louvres so compressed.

7. The combination with a gas burner embodying a central inlet flue and flues branching therefrom and spaced apart, of a band adjustable to circumference to encircle the extremities of the arms, and inwardly struck louvres formed in the band and compressible to vary the heights of certain of said louvres adapted to bear upon the extremities of the arms and maintain the band in encircling position at a height above the burner determined by the proportion of said louvres so compressed.

In testimony whereof I have signed my name to this specification.

EDWIN HUMPHREYVILLE.
